Des. 192,925
Patented May 29, 1962

192,925

BIRD FEEDER

Melvin Harold Kofsky, New Hyde Park, and Albert E. Karp, Flushing, N.Y., assignors to Cal-Cod Process Corp., Maspeth, N.Y., a corporation of New York

Filed Oct. 17, 1961, Ser. No. 67,126

Term of patent 14 years

(Cl. D31—2)

FIG. 1

FIG. 2

FIG. 3

FIG. 4

FIG. 7

FIG. 8

FIG. 5

FIG. 6

FIG. 1 is a front perspective view of a bird feeder showing my new design;

FIG. 2 is a top plan view thereof;

FIG. 3 is a front elevational view thereof;

FIG. 4 is a side elevational view thereof;

FIG. 5 is a bottom plan view thereof;

FIG. 6 is a rear elevational view thereof;

FIG. 7 is a section along line 7—7 of FIG. 1; and

FIG. 8 is a section along line 8—8 of FIG. 3.

The side not shown is substantially the same as the side shown.

We claim:

The ornamental design for a bird feeder, substantially as shown and described.
